Primary Examiner — Ricky Pham(74) *Attorney, Agent, or Firm* — Connolly Bove Lodge & Hutz LLP(57) **CLAIM**

The ornamental design for a rice cooker, as shown and described.

DESCRIPTION

FIG. 1 is a perspective view of the rice cooker with the lid closed;

FIG. 2 is an exploded perspective view of the rice cooker with steamer insert;

FIG. 3 is a front view of the rice cooker shown in FIG. 1;
FIG. 4 is a side view of the rice cooker shown in FIG. 1;
FIG. 5 is a top view of the rice cooker shown in FIG. 1;
FIG. 6 is a bottom view of the rice cooker shown in FIG. 1;
FIG. 7 is a cross-sectional view of the rice cooker and steamer insert along A-A shown in FIG. 5;

FIG. 8 is a perspective view of the steamer insert, shown separately for completeness of illustration;

FIG. 9 is a top view of the steamer insert of FIG. 8;

FIG. 10 is a bottom view of the steamer insert of FIG. 8;

FIG. 11 is a front view of the steamer insert of FIG. 8; and,

FIG. 12 is a side view of the steamer insert of FIG. 8.
